CLOTHES WRINGER

George Walen, Tyner, Saskatchewan, Canada

Application March 24, 1933, Serial No. 662,554
In Canada March 24, 1932

7 Claims. (Cl. 68—32)

This present invention relates to improvements in a clothes wringer and appertains particularly to an attachment therefor in the form of a safety guard and a feeding belt.

5 An object of the invention is to provide a wringer attachment comprising removable frames attached to opposite sides of the wringer and carrying an endless feed belt passing between the regular wringer rollers.

10 A further object of the invention is to provide a wringer attachment of this kind that can be applied easily to any standard clothes wringer of conventional design and as easily removed or interchanged as desired.

15 A further object of the invention is to provide a safety guard in the form of removable frames on opposite sides of the clothes wringer carrying an endless feed belt and supplied with belt supporting platforms under the upper load carrying 20 side of the belt.

25 A further object of the invention is to provide a safety feeding attachment for clothes wringers including removable and interchangeable feeding and delivering end frames carrying a table supported endless belt adapted to take the articles to be introduced to the rollers at a safe distance ahead thereof and after passing them between the wringer rollers to deliver the same to a waiting basket or tub placed conveniently beneath the delivering end.

30 A still further object of the invention is to provide a clothes wringer safety attachment of the nature and for the purposes described that is characterized by structural simplicity, durability 35 and operating efficiency and being capable of manufacture and sale at a reasonable cost is thereby rendered commercially desirable.

To the accomplishment of these and related objects as shall become apparent as the description proceeds, my invention resides in the construction, combination and arrangement of parts as shall be hereinafter more fully described, illustrated in the accompanying drawing, and pointed out in the claims hereunto appended.

45 The invention will be best understood and can be more clearly described when reference is had to the drawing forming a part of this disclosure wherein like characters indicate like parts throughout the several views.

50 In the drawing:—

Figure 1 is a side elevation of a conventional clothes wringer equipped with my safety feed attachment;

55 Figure 2 is a horizontal section thereof as taken

on the line 2—2 of Figure 1, looking in the direction indicated by the arrows;

Figure 3 is a vertical longitudinal section as taken on the line 3—3 of Figure 2, looking in the direction indicated by the arrows; and

Figure 4 is an elevational detail of the connecting device by which the removable frames attach to the wringer proper.

To the wringer 5 are applied four screw eyes 6, one on the forward and rear face of each end 10 post 7 and all at the same height.

A forward or feeding end frame 8 and a rear or delivery end frame 9 attach interchangeably to opposite sides of the wringer 5, though both frames are similar in structural elements they 15 appear different in design and will be described individually later. Both end frames are composed of spaced sides 10 of sheet metal held together by a pair of transverse rods 11 and each of the sides 10 of the end frames 8 and 9 are bent 20 outwardly in flanges 12 at their approaching or confronting ends that are extended vertically in both directions to give substantial bearing surface against the wringer ends 7 to which these out-turned flanges 12 are applied. These flanges 25 12 are each cut away a short distance from the top, and opposite these cut outs and just spaced in from the wringer contacting end, the opposite frame sides 10 are provided with registering perforations 13 through which the intermediate portion of the transverse connecting pins 14, held by the screw eyes 6, extend. These connecting pins 30 14 are preferably bent as at 15 at one end.

At their outer ends, each of the frames 8 and 9 carry transverse idling rollers 16 around which 35 an endless canvas feed belt 17 runs, its upper side passing between the rollers of the clothes wringer 5. A supporting table 18 is included with each of the end frames 8 and 9 lying immediately under the upper or load carrying side of the belt 40 17 by resting on the transverse rods 11, their opposite ends 19 being rolled downwardly around said rods.

The forward or feed end frame 8 differs, as mentioned previously, from the rear or delivery 45 end frame 9 in that it is shorter, extending forwards from the wringer 5 a less distance than the rear delivery frame 9 continues back of or beyond the wringer; furthermore its idling roller 16 is lower than the bottom of the wringer's rollers whereas the idling roller 16 of the rear or delivery frame 16 is raised above it though their alignment is below the axis of the lower wringer roller so that the belt 17 is stretched upwardly to pass over.

It will be seen, as a consequence of the difference between the relative locations of the idling rollers 16 in the feed and delivery frames 8 and 9, that their side members 10 will vary in configuration and the length of their supporting tables 18 will differ considerably. It may also be pointed out that the end of the table 18, in the feed frame 8, nearest the wringer rollers may be rolled back, as at 20, similar and not opposite to the far end thereby corresponding to or concentric with the adjacent wringer roller.

In use, the clothes to be passed through the wringer are dropped on the advancing canvas belt 17 carried untouched through between the wringer rollers, cut the length of the rear frame and dropped into a waiting tub or basket. To remove the device, the belt 17 can be broken at its seam and the two pins 14 withdrawn allowing the frames 8 and 9 to fall free. These latter are interchangeable and can be applied to either side of the wringer as desired.

From the foregoing description taken in connection with the accompanying drawing, it will be manifest that a clothes wringer is provided that will fulfill all the necessary requirements of such a device but as many changes could be made in the above description and many apparently widely different embodiments of my invention may be constructed within the scope of the appended claims without departing from the spirit or scope thereof, it is intended that all matters contained in the said accompanying specification and drawing shall be interpreted as illustrative and not in a limitative or restrictive sense.

Having thus described the invention, what is claimed is:—

1. In combination with a wringer, a safety feed attachment comprising a feed frame extending forwardly and downwardly from said wringer; a delivery frame extending backwardly and upwardly from said wringer, said feed and delivery frames being individually removably applied to opposite sides of said wringer and an endless belt running around said frames.

2. In combination with a wringer, a safety feed attachment comprising an endless feed and delivery belt passing between the wringer rollers on an inclined plane and around a pair of idling rollers for said belt on opposite sides of said wringer supported at different heights one above and one below said wringer rollers by individual and removable frames.

3. A safety feed attachment for a wringer comprising a frame formed of a pair of side walls, transverse rods and an idling roller between said walls, an endless belt riding around said idling roller and a removable supporting table having downwardly curved opposite ends resting on said transverse rods and lying immediately below the load carrying side of said belt for supporting the same.

4. A safety feed attachment for a wringer comprising a frame formed of a pair of side walls, transverse rods and an idling roller between said sides, out-turned flanges on the ends of said side walls against the wringer and perforations in the top of said side walls near said flanged ends to accommodate a transverse connecting pin by which said frame attaches to the wringer.

5. A safety feed attachment for a wringer comprising a frame formed of a pair of side walls, transverse rods and an idling roller between said sides, out-turned flanges on the ends of said side walls against the wringer cut away near the top to accommodate screw eyes projecting from the wringer, perforations in said side walls opposite the cut away part of said flanges, and a transverse connecting rod bent at one end adapted to extend through said perforations intermediate of its ends that are supported in said screw eyes.

6. In combination with a clothes wringer, a safety feed attachment and supporting table comprising a pair of interchangeable end frames removably supported on opposite sides of said wringer, an idling roller disposed transversely in the outer end of each of said end frames that carried by the forward or feeding end frame being lower than the bottom wringer roller and that carried by the rear or delivery end frame being higher and the alignment of said idling rollers being below the bottom wringer roller and an endless canvas belt running around said idling rollers and between the wringer rollers.

7. A safety attachment for wringers and the like comprising individual and interchangeable feed and delivery frames; means for connecting the same to opposite sides of a wringer and an upwardly inclined endless belt, having its ends supported at different heights by said frames, running around the same.

GEORGE WALEN.
